5 Claims. (Cl. 103—53)

1

This invention relates to fuel pumps particularly adapted for internal combustion engines, and an object is to produce a new and improved fuel pump which is adapted to deliver fuel under pressure to the carburetor and to return excess fuel from the carburetor to the supply tank or reservoir.

Another object is to provide a fuel pump of the above character which is electromagnetically operated, and has the new and improved features of construction, arrangement and operation hereinafter described.

Other objects and advantages will hereinafter appear and for purposes of illustration but not of limitation, an embodiment of the invention is shown on the accompanying drawings in which

Figure 1 is a side elevation partly in section of a fuel system for an internal combustion engine particularly adapted for vehicles showing the electromagnetic pump and carburetor with connecting duct lines, the carburetor being shown diagrammatically;

Figure 2 is an enlarged vertical sectional elevation of the electromagnetic pump;

Figure 3 is a sectional view substantially on the line 3—3 of Figure 2; and

Figure 4 is a transverse section on the line 4—4 of Figure 1.

This application constitutes a division of my copending application Serial No. 477,841, filed March 3, 1943, entitled "Fuel system for internal combustion engines."

The illustrated embodiment of the invention comprises a fuel system for internal combustion engines, more particularly engines for motor vehicles, and as shown, A represents an electromagnetic pump which is designed to pump liquid fuel from a tank T, through a tube 10 and force the fuel to a carburetor B through a tube 11. The pump A also operates to withdraw excess fuel from the carburetor B through the tube 12. Thus while the engine is operating, a continuous flow of gasoline is maintained through the carburetor and this is important for keeping the carburetor relatively cool and militating against fuel loss caused by heat from the carburetor. Ample fuel is retained in what might be termed a constant level chamber so that even though the vehicle is on an extremely sharp upward incline, sufficient pressure head will be maintained at all times in the region of the jet. Furthermore, the carburetor is so designed that when the engine is idle, the fuel drains from the constant level chamber.

2

Referring more particularly to the drawings, the electromagnetic pump A comprises a block 14 and a block 15 between which is clamped a flexible diaphragm 16, a series of cap screws 17 securing the blocks together and retaining the diaphragm 16 in position. As will hereinafter appear, the block 15 is formed with ports, passages and provided with valves for controlling the flow of liquid fuel from the tank T to the carburetor B and the block 14 is provided with ports, passages and valves controlling the flow of fuel from the carburetor to the tank.

A pump chamber 17 enables reciprocatory flexing operation of the diaphragm 16 to effect the desired pumping operation and clamped on opposite sides of the diaphragm are discs 18 and 19 which fit over a reduced end 20 of a vertically reciprocating plunger 21. Suitable means is provided for securely retaining the discs 18 and 19 on the reduced end portion 20 so that as the plunger 21 reciprocates, the diaphragm will effect the desired pumping action within the chamber 17. The upper portion of the plunger 21 has a sliding fit within a cylinder 22 which is integral with and projects upwardly from the upper portion of the block 14. Intermediate the upper portion of the plunger 21 and the lower reduced end portion 20 is an intermediate reduced portion 23 of somewhat less diameter than the inner diameter of the cylinder 22. The plunger 21 is formed with an axially extending socket or bore 24 which is open at its upper end and terminates in the intermediate portion 23 at its lower end. Directly beneath the bore 24 is a slightly smaller bore 25 and directly beneath the bore 25 is a still smaller bore or socket 26.

Seated at the lower end of the bore 24 is a washer 27 against which abuts the lower end of a coil spring 28. The upper end of the coil spring 28 bears against the under side of a plug 29 which fits in and closes the upper end of the cylinder 22. The plug 29 is retained in place by pins 30 and a suitable sealing ring 31 carried by the plug provides an effective seal between the plug and the cylinder. It will be manifest that the plunger 21 is slidable within the cylinder 22 and causes reciprocatory flexing movement of the diaphragm 16.

Slidably centrally through the plug 29 is a switch operating pin 32 which passes through the coil spring 28 and the washer 27. At the lower end of the pin 32 is a head 33 which is adapted to abut against the under side of the washer 27 in the downward movement of the plunger, and 55 to abut against the shoulder forming the lower

end of the bore 25 when the plunger moves upwardly. The upper end portion of the switch operating pin 32 is snugly engaged in leak proof manner by a resilient disc 34 preferably of synthetic rubber. As shown, the upper end of the plug in the region of the central portion of the disc 34 is recessed as indicated at 36. The disc 34 fits in liquid tight contact within a socket provided in the plug 29 and is clamped in place by a plate 35 which has an upwardly embossed portion 37 to afford limited flexing movement of the disc in a path defined by the embossed portion 37 and the recess 36 during the reciprocatory movement of the switch operating pin 32.

The upper end portion of the operating pin 32 has a neck 38 which receives the notched end 39 of an upwardly bowed spring contact plate 40. The spring plate 40 is integral with the cross plate 41 which has a contact point engageable with a contact point on a strip 42 mounted on a pair of insulating posts 43. The cross plate 41 is integral with a pair of side plate members 44 which are integral with an end plate portion 45. The plate portion 45 fits in a suitable groove in an adjusting nut 46 which is threaded on a post 47. A nut 48 on the post 47 clamps the plate 35 in position.

Plates 51 and 52 are disposed at opposite ends of and are insulated from the solenoid coil, the plate 52 providing a mounting for the post 47. The insulating posts 43 are carried by the plate 35 and the latter is secured by screws 48a as well as the nut 48.

One terminal of the solenoid 49 or 53 as indicated on Figure 3, is electrically connected to the contact plate or strip 42. Also electrically connected to the opposite end of the plate 42 is a small resistance coil 54 which has its opposite end attached to an ear 55 struck up from the plate 52. The resistance coil 54 militates against arcing at the contact points when the latter are opened. The opposite terminal of the solenoid coil 49 extends to a source of electrical energy such as through the usual ignition switch 49a on the automobile so that when the ignition switch is turned to the "on" position, the solenoid 49 will be energized.

From the above description, it will be manifest that the switch is of the simple over-center spring type, the arched or bowed spring 40 being such that when the switch operating pin 32 reaches a predetermined position in downward movement, the contacts will be closed and when in a predetermined upper or raised position, the contacts will be open. It will further be understood that the reduced bore 25 in which the head 33 of the operating pin is disposed, is of sufficient depth that as the plunger 21 moves downwardly under the influence of the coil spring 28, the head 33 will be engaged by the washer 27 slightly before the diaphragm 16 has completed its downward pumping movement, whereupon the contacts will be closed to cause the solenoid 49 to be energized thereby to cause the plunger 21 to move upwardly. Such upward movement continues until the shoulder at the bottom end of the reduced bore 25 engages the head 33 of the operating pin, again to operate the switch to de-energize the solenoid 49. When the electric current is turned off, the diaphragm will assume the position shown in Figure 2 under the influence of the coil spring 28. A metallic cup-shaped housing 56 fits over the switch and solenoid parts and cooperates with the plates 51 and 52 to provide a path for

the magnetic flux, and may be held in place in any suitable manner.

The switch adjusting nut 48 should be turned so that the contact points are in open position slightly before the plunger 21 comes into contact with the plug 29 and in closed position slightly before the plunger reaches its lower limit of travel.

From the above description, it will be manifest that so long as the ignition switch 49a is "on," the diaphragm 16 will be flexed recurrently to effect a pumping action within the chamber 17 and arranged within the block 15 are valves 57 and 58 and within the block 14 are valves 59 and 60. The valves 57 and 60 are intake valves and the valves 58 and 59 are outlet valves. The arrangement is such that when the diaphragm 16 is flexed upwardly, liquid is drawn into the chamber 17 on the under side of the diaphragm from the inlet port 61 through the valve 57 and liquid which is on the upper side of the diaphragm 16 is forced past the valve 59 and from the block 14 through the outlet port 62. On the other hand, when the diaphragm 6 moves downwardly the liquid trapped on the under side of the diaphragm 16 is forced from the chamber 17 past the valve 58 and from the block 15 through the outlet port 63. At the same time liquid is drawn into the chamber 17 above the diaphragm 16 through the inlet port 64 and past the valve 60. Except for the different arrangement of the valves, they are of similar construction, each having a seating portion 65 which is backed up by a coil spring 66, the seating surface being substantially leak proof and of material resistant to gasoline, such, for example, as synthetic rubber.

Manifestly the valves are seated and unseated due to the difference in pressures. Although it is desirable that the several valve springs 66 be reasonably light, it is desirable that the valve spring for the valve 58 be somewhat stronger in order to hold that valve seated against the liquid pressure created when the fuel tank of the vehicle is elevated above the carburetor.

It will be observed that the fuel entering the block 15 through the port 61 does not pass directly to the valve 57. On the contrary, the fuel passes through a substantially L-shaped passage 67 to a sediment bowl 68, thence through a screen or filter 69 and through a passage 70 to the valve 57. A cap screw 71 holds the bowl 68 and filter screen 69 in place, the latter seating in the bowl as indicated.

The fuel from the pump A passing through the tube or duct 11 enters the carburetor B through a passage 72 which leads to a constant level chamber 73 having upstanding walls 74 forming with the wall 75 a four-sided chamber. The gasoline or other fuel is adapted to flow over the walls 74 into an overflow chamber 76 to the bottom wall of which is connected the pipe or tube 12. Thus it will be apparent that liquid fuel is forced into the constant level chamber 73 and thence may overflow the walls 74 into the overflow chamber 76 from which it is pumped through the tube 12. Through the wall 75 inclines upwardly a jet nozzle 77 which leads to the Venturi passage 78 in the air horn and can thence pass downwardly past the butterfly valve 79 to the engine cylinders, the top 80 being open in the usual manner. A small vent 81 leads from the chamber 73 to the air horn as indicated.

One important feature of the invention resides in the provision of a drain opening 82 in one of the walls 74 affording a communication between

the lower end portion of the chamber 73 and the overflow chamber 76, such drain opening being disposed below the entrance to the jet nozzle 77. This drain opening 82 is of paramount importance because it militates against so-called "percolation" of the gasoline when the engine is hot and not operating since it is effective in draining substantially all of the gasoline from the chamber 73 and thus from the region of the jet nozzle or nozzles 77. As a consequence, the constant level chamber 73 is free of gasoline at all times except when the engine and fuel pump A are in operation. It should be understood that the drain hole or tube 82 is relatively small and although fuel is constantly leaking through it, the amount is of no consequence during engine operation. The lower end of the overflow chamber 76 is somewhat deeper than the constant level chamber 73 so that liquid may flow readily through the drain tube 82.

If desired, the walls 14 of the constant level chamber 73 may incline inwardly toward the air horn or carburetor throat so that when the vehicle is climbing a grade, the fuel level may remain nearly constant or it may incline sharply upward thereby to cause the fuel level to be raised under these conditions. In any case, however, the level of the fuel in the chamber 73 is lowered relatively to the jet nozzle 77 when the vehicle is descending a grade. As shown in Figure 4, the constant level chamber 73 at least partially surrounds the carburetor throat so that when the carburetor is tilted to the right as viewed in Figure 1, liquid fuel is maintained at nearly a constant level with respect to the jet nozzle 77.

In some cases it may be desirable to control the operation of the pump A by means of a thermostatic switch which would be responsive to carburetor temperature so that even when the engine is idle, the pump would be in operation should the carburetor temperature exceed a predetermined maximum.

It is to be understood that numerous changes in details of construction, arrangement and operation may be effected without departing from the spirit of the invention especially as defined in the appended claims.

What I claim is:

1. A fuel pump of the type having a pumping chamber of constant displacement, a diaphragm operable in said chamber, means for actuating said diaphragm in one direction and spring means for actuating said diaphragm in the opposite direction, said pump comprising a pair of inlet and outlet valves on opposite sides of the diaphragm whereby upon actuation of said pump in one direction fluid is drawn through the inlet valve on one side of the diaphragm, while fluid on the other side of the diaphragm is discharged through the outlet valve, said valves being spring tensioned and the outlet valve on the feed side having a slightly stronger spring to counteract the additional force of the fluid head.

2. In a fuel pump of the type having a casing defining a pumping chamber, a diaphragm operable in said chamber, a pair of inlet and outlet valves on opposite sides of the diaphragm whereby upon actuation thereof in one direction fluid is drawn through the inlet valve on one side and fluid is discharged through the outlet valve on the other side, flat rigid discs disposed on opposite sides of the diaphragm, a cylinder rigid with said casing and projecting outwardly from

one side of the chamber, a plunger secured at one end to a central portion of the diaphragm and sliding in said cylinder, solenoid motor means for actuating the movement of said plunger in one direction, and spring means for actuating the movement of said plunger in the opposite direction, a pin mounted coaxially and enclosed by said plunger and slideable therein with one end portion extending therethrough, a flange associated with the enclosed portion of said pin, abutment surfaces associated with said plunger relating the final reciprocatory movement of said plunger to said pin thereby transmitting delayed like reciprocatory movements thereto, abutment surfaces on the free end of said pin, and means in cooperation with said pin abutment surfaces for rendering said solenoid motor means operable upon movement in said one direction and inoperable upon movement in the opposite direction.

3. In a fuel pump of the type having a casing defining a pumping chamber, a diaphragm operable in said chamber, a pair of spring tensioned inlet and outlet valves on opposite sides of the diaphragm, a cylinder rigid with said casing and projecting outwardly from one side of the pumping chamber, a plug fitting the outer end of the cylinder, a sealing ring fitting a recess in said plug and abutting the cylinder surface thus serving as a barrier to the passage of fluids or vapors, a plunger reciprocable within said cylinder and fixed at its inner end to said diaphragm, solenoid motor means for actuating the movement of said plunger in one direction, and spring means for actuating the movement of said plunger in the opposite direction, said spring means being disposed within said cylinder with one end abutting against said plug, the other end seating upon a shoulder within said plunger, a pin disposed coaxially within said plunger and slideable through said plug beyond which said pin extends, a flange associated with the enclosed portion of said pin, spaced abutments associated with said plunger engageable with the flanged portion of said pin for recurrently actuating the same in one direction or the other in response to plunger movement, spaced abutments on the free end portion of said pin, and means associated with said pin abutment surfaces for rendering said solenoid motor means operable upon movement in said one direction and inoperable upon movement in the opposite direction.

4. In a fuel pump of the type having a casing defining a pumping chamber, a flexible diaphragm operable in said chamber, a pair of spring tensioned inlet and outlet valves on opposite sides of the diaphragm, the spring for the outlet feed valve being slightly stronger than the springs of the remaining valves to compensate for the added force of the fluid head, a cylinder rigid with said casing and projecting outwardly from one side of the pumping chamber, a fluid tight plug fitting the outer end portion of the cylinder, a plunger reciprocatory within the cylinder and fixed at its inner end to the diaphragm, a disc seating upon a shoulder within said plunger, solenoid motor means for actuating the movement of said plunger in one direction and spring means for actuating the movement of said plunger in the opposite direction, said spring means being disposed within said cylinder with one end abutting against said plug and the other end seating upon said disc, a pin slideable through said plug and arranged

with a portion extending within said cylinder, a resilient disc snugly engaging the pin at the central portion, means for anchoring the edge portions of said disc thereby to provide a liquid seal for said pin, a flange integral with the enclosed end portion of said pin, spaced abutments associated with said plunger engaging the flanged portion of said pin for recurrently actuating the same in one direction or the other in response to plunger movement, spaced abutments on the free end portion of said pin, and means in cooperation therewith for rendering said solenoid motor means operable upon pin movement in said one direction and inoperative upon movement in the opposite direction.

5. A fuel pump as claimed in claim 4, in which the spaced abutments associated with said plunger are comprised of the disc seating upon the shoulder within the plunger and against which the spring bears, and another shoulder 10 20

formed by a bore of smaller diameter continuing downwardly within the plunger, the distance between abutments being spaced for contact with the end portion of the pin during the final movements of the plunger in the upwardly or downwardly direction.
